US00D929087S

(12) **United States Design Patent** (10) Patent No.: **US D929,087 S**
(45) Date of Patent: ** *Aug. 31, 2021

(54) **SHOE**
(71) Applicant: **NIKE, Inc.**, Beaverton, OR (US)
(72) Inventor: **Kristina Gerig**, Portland, OR (US)
(73) Assignee: **NIKE, Inc.**, Beaverton, OR (US)
(*) Notice: This patent is subject to a terminal disclaimer.
(**) Term: **15 Years**

(21) Appl. No.: **29/709,185**
(22) Filed: **Oct. 11, 2019**

Related U.S. Application Data

(63) Continuation of application No. 29/648,238, filed on May 18, 2018, now Pat. No. Des. 874,104, and a continuation-in-part of application No. 29/648,244, filed on May 18, 2018, now Pat. No. Des. 862,853.

(57) CLAIM

The ornamental design for a shoe, shown and described.

DESCRIPTION

FIG. 1 is a front side view of a shoe showing my design; FIG. 2 is a first side rear perspective view thereof; FIG. 3 is a rear view thereof; FIG. 4 is a second side rear perspective view thereof; and, FIG. 5 is a second view thereof.

The even-length broken lines depict unclaimed subject matter and form no part of the claimed design. The oblique line shading depicts a surface that is transparent, translucent, highly polished, or reflective.

1 Claim, 5 Drawing Sheets

FIG. 1.

FIG. 2.

FIG. 3.

FIG. 4.

FIG. 5.
